UNITED STATES PATENT OFFICE.

FERDINAND SCHOETTLE, OF GERMANTOWN, PENNSYLVANIA, ASSIGNOR TO PIONEER SUSPENDER COMPANY, A CORPORATION OF PENNSYLVANIA.

DESIGN FOR A BOX.

No. 39,344.

Specification for Design.

Patented June 9, 1908.

Application filed March 25, 1908. Serial No. 423,282. Term of patent 14 years.

To all whom it may concern:

Be it known that I, FERDINAND SCHOETTLE, a citizen of the United States, residing at 417 Wister street, Germantown, county of Philadelphia, State of Pennsylvania, have invented a new, original, and ornamental Design for Boxes, of which the following is a specification, reference being had to the accompanying drawing, forming part thereof.

The figure is a perspective view of a box, showing my new design.

I claim:

The ornamental design for a box, as shown.

FERDINAND SCHOETTLE.
